[57] CLAIM

The ornamental design for a film-loaded cartridge, as shown and described.

DESCRIPTION

FIG. 1 is a top plan view of a film-loaded cartridge showing our new design;

FIG. 2 is a front elevational view thereof;

FIG. 3 is a bottom view thereof;

FIG. 4 is a right side elevational view thereof;

FIG. 5 is a rear elevational view thereof; and

FIG. 6 is a left side elevational view thereof;

The broken line disclosure of the indicia in FIGS. 2 and 5 is for illustrative purposes only and forms no part of the claimed design.

FIG. 1

FIG. 2

FIG. 3

FIG. 4

FIG. 5

FIG. 6
